FABRIC BAND

Conrad J. Busch, Wyomissing, and Otto Eugene Huber, Reading, Pa., assignors to The Narrow Fabric Company, West Reading, Pa., a corporation of Pennsylvania

Original application March 13, 1936, Serial No. 68,702. Divided and this application May 27, 1936, Serial No. 81,992

3 Claims. (Cl. 66—172)

This invention relates to improvements in fabric bands, and particularly to a novel marginal construction which facilitates the attachment of the band by sewing and the use of a novel seam arrangement in conjunction therewith. This application is a division of application No. 68,702 filed March 13, 1936. The invention is particularly applicable to narrow fabrics such as tapes or bands provided with longitudinal ridges which may be formed by heavy longitudinal strands, a construction generally employed in elastic bands in which the longitudinal strands are composed of rubber or other elastic material.

Tapes or bands of this type are frequently attached to the margins of articles of wearing apparel to form an edging, one popular embodiment being the elastic garter band attached to the top of a knitted stocking. Although various methods of attachment have been proposed, there are definite advantages in sewing the band to the garment fabric, including particularly convenience and speed; but heretofore there have been certain practical difficulties which have detracted from the effectiveness and accuracy of the sewing operation.

One difficulty arises when the band includes longitudinal strands of rubber. In a band of this type some of the rubber strands must be located in the marginal portion of the band to assure uniform expansion and contraction; but this location renders them especially liable to be cut when sewing the marginal portion to the garment fabric. This difficulty is increased when the band is constructed of relatively loose material, such as certain desirable types of braided and warp knit bands; and there is a further complication when the garment fabric to which the band is attached consists of readily distorted material, such as knitted material, and especially the sheer knitted fabric of which stockings are usually made.

The general purpose of this invention is to provide an arrangement whereby the marginal portion of a band or the like provided with relatively heavy longitudinal ridges or strands may be sewed to fabric rapidly, accurately and without sewing into or across such strands. This is in general accomplished by providing a band or the like in which the longitudinal strands are located at predetermined intervals from the edge, providing seaming zones between the strands, adapted for sewing the band to the fabric with a multiple needle machine the needles of which are spaced relative to the longitudinal strands so that each needle is located between two strands

and produces on the face of the fabric a line of stitches located in a seaming zone. With this arrangement the seams are inconspicuous on the face of the band, as they lie in depressed portions between the longitudinal strands. The seams are preferably crossed and interlooped at the rear of the fabric in any of the various ways well known in the sewing machine art to provide an elastic composite seam which overlies the fabric, providing a firm support that is particularly advantageous for sheer stockings, permitting full elasticity of the band at the margin, and forming a neat binding for the fabric on the reverse side. These features are especially desirable in the manufacture of stockings, where neat appearance, strength and elasticity are of prime importance.

A further feature of the invention is the avoidance of thickening due to the superposition of the margin of the band upon the margin of the garment fabric. This is in general accomplished by employing a band which is provided with a substantially thinner marginal zone including longitudinal strands and extending across the area that is superposed upon the margin of the fabric by sewing. This thinner marginal zone may be produced by employing lighter threads in forming such zone; and a feature of the invention is the determination of the fact that the incorporation of such threads to form a zone of the type indicated is particularly feasible when the band is produced either by braiding or by warp knitting. The invention includes also certain specific constructions and methods of manufacture involved in the incorporation of such threads in bands of these types.

When the band is of relatively loose construction, as is frequently desirable to produce popular ornamental effects, the transverse threads have a tendency to slide along the longitudinal elastic strands and become bunched and distorted, particularly near the margin, producing an undesirable appearance and uneven support for the elastic strands. The arrangement above described eliminates this difficulty, as the seams hold the transverse strands longitudinally in place.

The properly spaced longitudinal strands adjacent to the margin likewise serve to guide and align the seam. They may be utilized in connection with guides usually employed in maintaining alignment of such margins; but the longitudinal strands have a further guiding effect through the action of the needles themselves, the sloping points above which tend to shift laterally a longitudinal strand which has come too close to the

needle, so that the seam tends to register itself between the adjacent parallel strands. This is particularly effective where a plurality of parallel seams are sewed between parallel strands by a 5 multiple needle machine as above indicated.

A further purpose of the invention is to provide an elastic band adapted for attachment by sewing to an expansible garment margin arranged so that the band will have substantially uniform 10 longitudinal expansion and tension throughout its width. Bands of this type have heretofore been constructed and attached in such manner that certain portions thereof were less extensible, particularly along the line of the seam; and the 15 result was an objectionable constriction of the band against the wearer along the line of the less extensible portion. This defect is eliminated according to the present invention by employing a band having uniform longitudinal extensibility 20 throughout its width, and attaching it by a seam sufficiently expansible to permit full and free stretching of the portion of the band engaged by the seam.

Other objects and advantages will appear from 25 the following description when considered in connection with the accompanying drawings, in which

Fig. 1 is a face view of a braided elastic band attached to the margin of a relatively sheer garment fabric;

Fig. 2 is a similar view showing a warp knit elastic band;

Fig. 3 is a face view of a braided elastic band attached to the top of a knitted stocking to form 35 a garter selvedge therefor;

Fig. 4 is a fragmentary view on line 4—4 of Fig. 3, showing the attaching zone with finer threads incorporated in the attaching zone of the elastic band;

Fig. 5 is a view similar to Fig. 4 in which standard size threads are employed in the attaching zone;

Fig. 6 is a sectional view of the fabric and band at the attaching zone with the needles and associated parts of a sewing machine in position for sewing the band to the garment fabric;

Fig. 7 is a diagrammatic illustration of a method of braiding an elastic band such as that shown in Figs. 1 and 3, with the central portion 50 omitted;

Fig. 8 is a diagrammatic view illustrating a method of manufacture of a warp knit elastic band such as that shown in Fig. 2, the central portion being omitted; and

Fig. 9 illustrates diagrammatically a suitable compound seam.

Considering first the braided band 10, shown in Figs. 1 and 4, it includes a lower marginal zone 11 in which four longitudinal strands 12 are incorporated, which are connected by transverse strands indicated generally at 13. This construction produces a plurality of longitudinal ridges corresponding to the location of strands 12, and a plurality of substantially thinner zones intermediate the ridges which constitute the seaming zones 14. These zones are spaced in conformity with the spacing of the needles of a cooperating multiple needle sewing machine so that the seams produced thereby will be accurately located between longitudinal strands 12.

This arrangement is shown best in Fig. 6, in which the strands 12 are located at the sides of needles 15 and overlie the upper margin of the stocking fabric 16 resting on the bed-plate 17 of 75 the machine and held in position thereon by

presser foot 18. By the employment of well known suitable guiding arrangements the general relationship between fabric 16 and the marginal zone 11 of band 10 may be readily maintained; and the spacing of longitudinal strands 12, in conjunction with the tendency of the needle points to push the larger strands away from the seams, will serve to restrict the seams to the zones 14 and prevent sewing across strands 12. When the latter are constructed of rubber they are readily cut when penetrated by the needles, seriously detracting from the elasticity of the band 10.

It is especially advantageous to employ a seam in which the threads carried by the various needles are interlooped or cross-connected below fabric 16 to produce an elastic seam, various seams of this type being well known. An arrangement of this type is indicated diagrammatically in Figs. 4, 5, and 9 in which the face seams 19 have the appearance of ordinary seams but are transversely connected at 20 beneath the fabric 16. One type of compound seam structure suitable for the purpose is illustrated in Fig. 9. It includes three needle threads and three looper threads, and can be produced by three-needle sewing machines of a standard type. Seams 19 are formed by needle threads 43, 46 and 49 the stitches 44, 47 and 50 of which are located between longitudinal warp strands 12 or 28 and serve to maintain the weft strands 13 or 30 in position on the warp strands. The looper threads 52, 53, and 54 engage loops 45, 48, and 51 of the needle threads to form an elastic seam.

Under certain circumstances it is advantageous to reduce the excess thickness of the overlapping sewed portions of band 10 and fabric 16, which may be accomplished by employing a relatively thinner marginal zone 11 on band 10. This may be produced by forming such zone from finer threads. A method of making a braided band 40 10 having these characteristics is shown in detail in Fig. 7. In this illustrative embodiment the band includes a first marginal zone 11 (shown at the lower edge in Figs. 1, 3, and 4) which is solidly 45 braided, including four longitudinal elastic strands 12; a central zone including longitudinal elastic strands 21, the central portion of which duplicates the remainder thereof as shown in Fig. 1, and is therefore omitted from the illustration; and a second margin including four longitudinal 50 elastic strands 22. The elastic strands are interconnected by transverse strands 23 extending back and forth across selected portions of the central zone and a second margin of the band 10 and by transverse strands 24, preferably finer 55 than strands 23, traversing the first marginal zone 11 and extending around the elastic strands 12. The transverse strands 23 and 24 are preferably inelastic.

The pattern employed is subject to extensive 60 variations as will be apparent to those skilled in this art. In the particular pattern shown in Fig. 7 the spindles are indicated generally at 25 and the tellers or quoits at 26, with the path of the strand carried by each spindle 25 indicated 65 diagrammatically in the usual manner, the travel of each spindle 25 around a teller or tellers 26 being controlled in the ordinary way by jacquard mechanism. It will be noted that the elastic strands 12 retain the same general location and will be straight in the finished braid; while the finer transverse strands 24 interbraid strands 12 with each other and are marginally interbraided with selected transverse strands 23 to preserve 70 the continuity of the braid.

Another type of band adapted for use in connection with this invention is the warp knit type illustrated generally at 27 in Fig. 2. It is provided with similar longitudinal elastic strands 28 in the 5 first marginal zone 11a, transversely connected by finer strands to produce seaming zones as already described. One method of producing a braid of this type is illustrated in Fig. 8, which shows diagrammatically an arrangement applicable to a 10 warp knitting or "Raschel" machine of the well known type. The specific band illustrated is produced by feeding the main longitudinal or warp strands downwardly to a single bank of needles, knitting a weft thread around each warp strand, 15 and connecting the weft threads transversely to form a band. In the preferred form the warp strands are elastic and the weft threads in the marginal zone 11a may be of substantially finer size to provide a thinner marginal zone.

20 In the arrangement shown, the weft threads which wrap the longitudinal strands are carried by the first finger bar 29, and include the finer weft threads 30 which wrap the strands 28 in the first marginal zone 11a (shown at the lower edge 25 in Fig. 2) as well as the remaining weft threads 31 the size of which is determined by the pattern, and which wrap the remaining longitudinal strands 32. The longitudinal strands 28 and 32 are carried by the fourth finger bar 33. Intermediate strands are provided for interlocking adjacent wrapping weft threads. Certain of the 30 interlocking strands in the form illustrated extend in a zigzag path between the wrapping weft threads of the marginal portions and interlock 35 all contiguous loops of the wrapping weft threads. These continuous interlocking threads are carried by the third finger bar 34, and include the continuous interlocking threads 35 for the outer margin which engage strands 31, and preferably finer 40 continuous interlocking threads 36 engaging the wrapping strands 30 in the marginal zone 11. The intermediate portion of the band may be patterned by providing suitable spaces or openings, a convenient arrangement including interlocking 45 threads 37 on the second finger bar 38 which connect spaced loops of adjacent wrapping weft threads 31 to form a suitably patterned structure. The construction and arrangement is such that each wrapping weft thread 30 and 31 is connected 50 to each adjacent wrapping weft thread by an interlocking thread 35, 36, or 37 forming a continuous band structure. The central portion of the band is omitted as it includes simply a repetition of the adjacent portions, as will be evident 55 from Fig. 2.

A novel margin structure has been provided along the upper edge of the band 27. It includes a special edging strand 39 carried by the fifth finger bar 40. Strand 39 is arranged to form a 60 series of free loops 41 interlocked at their inner bights 42 with one or more of the wrapping weft threads 31. This is accomplished by wrapping strand 39 around an idle needle to form the free outer bight of each loop 41, and interlocking the 65 inner bight 42 with a weft thread 31 by bringing strand 39 across into locking position in the usual manner. This interlocking may take place at

desired intervals as determined by the usual pattern mechanism to provide loops 41 of any preferred length. The interlocked bights 42 of such loops 41 may also be carried across the needles into position to be interlocked by more than one 5 of the wrapping weft strands 31, as shown, providing a firmer anchorage for the marginal loops.

The specific embodiment of warp knitted braid which has been illustrated and described is adapted to be manufactured by the use of a single bank 10 of needles. The bars are mentioned in order as they appear from the fabric side of the needles; and may be manipulated by the pattern mechanism in a manner obvious to those skilled in the art by shogging the first bar at the loop side of 15 the needles, and appropriately shogging the remaining bars at the fabric side. Other details will be apparent from a study of the relative positions of the various threads and strands as shown in Fig. 8.

20 It will be noted that both the braided band 10 and the warp knit band 27 are constructed so as to be uniformly extensible longitudinally throughout their width; and that the seam is of a type that will permit the engaged portions of 25 the band to expand without material restriction.

While the invention is particularly suitable for use with elastic bands of the braided or warp knitted type indicated, certain features thereof are not limited to such a construction. For instance, the longitudinal ridges may be produced in other ways than by longitudinal strands. The particular proportions, arrangement and method of sewing may be substantially varied from that above set forth, and various braiding and warp 30 knitting patterns may be used. The word "garment" is used as synonymous with "article of 35 wearing apparel" and similar expressions.

We claim:

1. A fabric band of uniform expansibility comprising longitudinal and transverse strands and having a relatively thinner marginal portion formed with transverse strands of lesser diameter than the transverse strands in the remainder of the band and provided with longitudinal 45 strands forming a needle track portion.

2. A fabric band of uniform expansibility comprising longitudinal strands and transverse strands, said band having a relatively thinner marginal portion formed with transverse strands 50 of smaller diameter than the transverse strands in the remainder of the band, said transverse strands of smaller diameter cooperating with certain of said longitudinal strands to form a needle track and extending only across the thinner marginal portion.

3. A self-guiding fabric band having a relatively thinner marginal portion including a plurality of parallel longitudinal rubber strands defining intermediate seaming zones, said zone 60 forming paths for needles of a multiple needle sewing machine operating in the seaming zones, arranged to maintain alignment with the needles in said zones by lateral engagement of the rubber strands with said needles.
